(74) Attorney, Agent, or Firm—Womble, Carlyle, Sandridge & Rice, PLLC

(57) CLAIM

The ornamental design for a seat, as shown and described.

DESCRIPTION

FIG. 1 is a left front perspective view of a seat showing my new design;

FIG. 2 is a front perspective view thereof;

FIG. 3 is a side elevational view, the opposite side being a mirror image thereof;

FIG. 4 is a rear elevational view thereof;

FIG. 5 is a left front perspective view of a second embodiment of a seat showing my new design with the arms; and, FIG. 6 is a front perspective view thereof.

The views of the seat not shown form no part of the claimed design.

1 Claim, 6 Drawing Sheets
